UNITED STATES PATENT OFFICE.

OSCAR HAMMERSTEIN, OF NEW YORK, N. Y.

DESIGN FOR A SHIRT-COLLAR.

SPECIFICATION forming part of Design No. 26,304, dated November 17, 1896.

Application filed August 25, 1896. Serial No. 603,902. Term of patent 14 years.

To all whom it may concern:

Be it known that I, OSCAR HAMMERSTEIN, a resident of the city, county, and State of New York, have invented and produced a new and original Design for Shirt-Collars, of which the following is a specification, reference being had to the accompanying drawing, wherein the figure represents a back view of a shirt-collar embodying my design.

The leading feature of my design consists in a collar having the entire length of those portions of the neckband between the end button-tabs of considerably less extent transversely than the body of the collar.

In the drawing, A represents the main body portion of the collar, and B represents the neckband. This neckband terminates at each end in the usual end buttonhole-tabs *a*, intermediate of which is a central buttonhole-tab or enlarged portion *b*, which depends from the middle of the neckband B. Between each of the buttonhole-tabs *a* and the central buttonhole-tab *b* the neckband is recessed,

as indicated at *c d*, so that the neckband at these portions is of considerably less extent 25 transversely than the body proper A of the collar. The advantage of making a shirt-collar of this configuration is that no bearing whatever is afforded at the neckband for contact with the shoulders or sides of the 30 neck of the wearer, which would result in the collar riding up on the neckband of the shirt. At the same time it will be observed that ample bearing for the collar is provided at those 35 portions of the neckband where it is necessary to secure the collar to the neckband of the shirt and where there is no liability of the collar riding up.

What I claim is—

The design for a shirt-collar substantially 40 as herein described and shown in the accompanying drawing.

OSCAR HAMMERSTEIN.
